UNITED STATES PATENT OFFICE.

HENRY A. SPAULDING, OF CHICAGO, ILLINOIS, ASSIGNOR TO SPAULDING & COMPANY, OF SAME PLACE.

DESIGN FOR A SPOON.

SPECIFICATION forming part of Design No. 21,041, dated September 15, 1891.

Application filed May 11, 1891. Serial No. 392,402. Term of patent 7 years.

To all whom it may concern:

Be it known that I, HENRY A. SPAULDING, a citizen of the United States, residing at Chicago, in the county of Cook and State of Illinois, have invented and produced a new and original Design for a Spoon, of which the following is a specification, reference being had to the accompanying illustration, forming part thereof.

10. The illustration shows a top or face view of a spoon embodying my design.

The predominant feature of my design is the representation upon the tip of the handle of a dwelling-house having a wing and porch at one side. Other incidental features are the following: a raised vine surrounding the representation of the dwelling-house and crossed below the same and continued down along

the sides of the handle nearly to the bowl. The handle is made with both major and minor enlargements, the former being at the tip and the latter being intermediate of the tip and the bowl. The bowl contains a representation of a wooden block-house or fort such as was common on the western frontier in the early history of the United States.

The names, words, and figures shown in the drawing of the design constitute no part of the design.

I claim—

15. The design for a spoon, substantially as herein shown and described.

HENRY A. SPAULDING.
